UNITED STATES PATENT OFFICE.

FRED LEWIS, OF LEJUNIOR, KENTUCKY.

MINER'S LAMP HOLDER.

Application filed August 10, 1925. Serial No. 49,378.

To all whom it may concern:

Be it known that I, FRED LEWIS, a citizen of the United States, residing at Lejunior, in the county of Harlan and State of Kentucky; have invented certain new and useful Improvements in Miners' Lamp Holders; and I do declare the following to be a full, clear, and exact description of the invention, such as will enable others skilled in the art 10 to which it appertains to make and use the same:

My invention relates to improvements in holders for miners' lamps of the type connected to caps. Devices of this character are 15 commonly formed partly from metal and partly of heat insulating material, and rivets are used for attaching the holder to the cap, the rivets being in contact with the metal and exposed at the inner side of the 20 cap, so that there is danger of conducting electricity to the miner's head if he should accidentally knock the lamp or the lamp holder against the usual overhead trolley wire. It is one object of the invention to 25 provide a new and improved lamp holder which is free of this objection.

Another object is to provide a holder for the ordinary carbide lamp, which is so engaged by the suspending hook of the lamp, 30 as to hold the latter in fixed angular relation with the cap, regardless of the direction in which the miner may move his head.

Yet another aim is to provide a device of 35 the class described which is of extreme simplicity, yet is efficient and very desirable.

With the foregoing in view, the invention resides in the novel subject matter herein-after described and claimed, the description being supplemented by the accompanying 40 drawing.

Figure 1 is a perspective view.

Figure 2 is a vertical sectional view.

Figures 3 and 4 are additional vertical sections on lines 3—3 and 4—4 of Fig. 1.

In the drawing above briefly described, 45 the numeral 1 designates a vertically disposed piece of leather or other desired heat insulating material, said leather piece having its upper end 2 directed rearwardly and 50 formed with an opening 3. A sheet metal plate is bent between its ends on a transverse line 4 to provide upper and lower plate-like portions 5 and 6 which are disposed at the upper and lower sides of the 55 end portion 2 of the leather piece 1, said plate-like portions 5 and 6 both terminating

in vertical parts 7 which are secured by rivets 8 against the vertical portion of the piece of leather 1 directly under the bend of the latter. Between the vertical part 7 60 of the upper plate-like portion 5 and the rear part of this portion, the metal is bowed forwardly from the leather as indicated at 9, this forwardly bowed portion being formed with a vertical slot 10. Behind the 65 bowed portion 9, an opening 11 is formed in the metal at the upper end of the opening 3. The part of the lower plate-like portion 6, between the rear end of the latter and its vertical front end, is downwardly offset 70 from the rearwardly directed end 2 of the leather piece 1, as indicated at 12, and this downwardly offset portion is formed with an opening 13 alined with the openings 3 and 11, so that all of the openings may readily 75 receive the usual hook 14 of a carbide lamp 15, the plate portion 5 being by preference formed with a plurality of grooves 16 leading to the opening 11 to assist in guiding the hook thereto. Moreover, this portion 5 80 preferably slants toward the opening 11 in a number of directions, as shown, thus further facilitating insertion of the hook. Reception of a portion of the hook in the slot 10, holds the lamp 15 against horizontal pivotal 85 movement, and reception of said hook in the vertically alined openings 11 and 13, prevents the lamp from swinging forwardly, when the miner tilts his head downwardly.

Near the rear end of the plate-like portions 5 and 6, rivets 17 are preferably passed through the former and the portion 2 of the leather piece 1, and additional rivets 18 by preference pass through said rear ends of the portions 5 and 6 and through the intervening portion 2 of the leather, so as to rigidly hold the several parts together. The rear ends of the portions 5 and 6 are reduced in width by notching them as indicated at 19, so as to expose the rear corners 90 of the leather, and through these exposed rear corners and the crown of the cap, rivets 20 are passed, and other rivets 21 pass through the lower corners of the leather piece and through the cap. The rivets 20 95 are entirely out of contact with metal and even should they be against the miner's head, they cannot conduct electricity thereto, should he accidentally strike the lamp or the plate portion 5 of the device against an 101 overhead trolley wire.

The device is exceptionally simple and in-

expensive, yet is a distinctly improved article which may be easily and cheaply manufactured and marketed, and will be highly efficient and in every way desirable.

5 Excellent results are obtainable from the exact details disclosed, and they are therefore preferably followed. However, within the scope of the invention as claimed, slight modifications may be made.

10 I claim:

1. A miner's lamp support comprising a vertical piece of non-metallic heat insulating material having a rearwardly directed upper end formed with a vertical opening, a 15 sheet metal plate bent substantially upon itself between its ends to provide upper and lower plate-like portions which contact with the upper and lower sides of said rearwardly directed end of the heat insulating material, 20 the free ends of said plate-like portions being vertically disposed and secured against the front and rear sides of the insulating member below the bend of the latter, the intermediate part of the upper plate-like por-

tion being forwardly offset from the heat insulating material and formed with a vertical slot and with an opening alined with the first named opening, the intermediate part of the lower plate-like portion being downwardly offset from the heat insulating material and being formed with an opening alined with the aforesaid openings, the three openings in the slot being adapted to jointly receive the hook of a carbide lamp, said openings being each of annular-walled 35 form to hold the hook against lateral movement.

2. A structure as specified in claim 1; the rear ends of said upper and lower plate-like portions being reduced in width to expose 40 corner portions of the piece of insulating material, whereby such corner portions may receive attaching rivets and may serve to insulate such rivets from the metallic parts of the device.

In testimony whereof I have hereunto affixed my signature.

FRED LEWIS.
